ADJUSTABLE FORM FOR BLOCKING AND PRESSING A SKIRT

James Elwood Waite, 2905 Garfield Ave., and William E. White, 5908 Marconi, both of Carmichael, Calif. 95608

Filed May 10, 1968, Ser. No. 11,880

Term of patent 14 years

Int. Cl. D10—08

U.S. Cl. D52—6

FIG. 1

FIG. 2

FIG. 3

The rear appearance of the device is a mirror image of the front seen in FIGURE 2.

We claim:

The ornamental design for an adjustable form for blocking and pressing a skirt, as shown and described.
